No. 36,809.

Patented February 16, 1904.

UNITED STATES PATENT OFFICE.

FREDERICK EDELMANN, OF WEEHAWKEN, NEW JERSEY, ASSIGNOR TO
THE KURSHEEDT MANUFACTURING COMPANY, OF NEW YORK, N. Y., A CORPORATION OF NEW YORK.

DESIGN FOR A COLLAR.

SPECIFICATION forming part of Design No. 36,809, dated February 16, 1904.

Application filed January 23, 1904. Serial No. 190,410. Term of patent 3½ years.

To all whom it may concern:

Be it known that I, FREDERICK EDELMANN, a citizen of the United States, residing at Weehawken, county of Hudson, and State of New Jersey, have invented a certain new, original, and ornamental Design for Collars, of which the following is a specification, reference being had to the accompanying drawing, forming a part hereof.

10 In the drawing the figure shows my design for collars, the repeats being shown in outline.

What I claim as new, and desire to secure by Letters Patent, is—

The ornamental design for a collar, substantially as herein shown. 15
